UNITED STATES PATENT OFFICE

BRADLEY DOBIE, OF ELMHURST, NEW YORK, ASSIGNOR TO AMERICAN ARCH COMPANY,
A CORPORATION OF DELAWARE

FURNACE-ARCH CONSTRUCTION

Application filed February 21, 1924. Serial No. 694,318.

My invention relates to furnace arch construction, and is especially concerned with the construction of the so-called "nose" and "ignition" portions of such arches, and the like. For convenience and brevity, both ignition and nose structures proper may conveniently be referred to as "noses". I aim to simplify and improve the nose construction generally; to make the first cost of such noses relatively low; and to minimize the subsequent expense for maintenance and repair. How these and other advantages can be realized in a novel manner through my invention will appear from my description hereinafter of selected and preferred embodiments.

In the drawings, Fig. 1 shows a vertical section through a nose construction conveniently embodying my invention.

Fig. 2 is a fragmentary sectional view, taken as indicated by the line 2—2 in Fig. 1.

Fig. 3 shows a longitudinal section through a steam boiler furnace arch with a somewhat different nose construction.

Fig. 4 is a similar fragmentary view of the latter nose construction on a larger scale than Fig. 3, at a different point in the arch transversely of the furnace.

Fig. 5 is a fragmentary sectional view, taken as indicated by the line 5—5 in Fig. 4.

Fig. 6 is a view similar to Fig. 3, illustrating a different embodiment of my invention in both nose proper and ignition structures.

Fig. 7 is a fragmentary sectional view similar to Fig. 5, taken as indicated by the line 7—7 in Fig. 6.

In Fig. 1, the main furnace arch is represented by a transverse bung of brick 8, with undercut heads 9 engaged by angle bar runners 10 held by clips 11 and suspended from any suitable means of support. The particular bung shown in Fig. 1 is suspended from part of the supporting means for the adjacent furnace nose, as will appear more fully hereinafter, and its brick 8 have a rabbeted shoulder conformation 14 for engaging and supporting filler brick (not shown) forming part of the main arch.

The nose 20 shown in Figs. 1 and 2 comprises sets of main brick 21 arranged in pairs, fantailwise, with their laterally undercut

heads 22 back to back and held between clips 23 bolted at opposite sides of sector-shaped supporting plates 24. Each of the plates 24 is bolted fast, at its upper corner, to a supporting member 27 (of T section) that is supported from a couple of I beams 28 extending transversely of the furnace. Preferably, the space between the I beams 28 is open through the side walls of the furnace, for circulation of air to cool the nose 20. As here shown, the member 27 is supported by means of a clamp 29 resting on the inner lower flanges of the beams 28 and bolted to the top flanges of said member 27. The main arch brick 8 adjacent the nose 20 are suspended from the corresponding ends of the supports 27, as by means of claws 59 taking through openings 60 in these members 27. On the opposite ends of the supports 27 rest curtain brick 31 that overlie the fantail brick 21. In the present instance, there is a space between the brick 31 and 21, which is filled by brick 51 resting on the latter, and by refractory cement or fireclay 61. All the various joints in the main and nose arches may be made tight with fireclay or other refractory cement, as usual.

Between the sets of main nose brick 21 are fantail sets of double filler nose brick 35 (Fig. 2) supported by the brick 21 by virtue of shoulder and rabbet engagement at 36. As will readily be seen, the weight of the brick 8 at one side of the fantail sets serves or tends to balance the brick 31, etc. at the other side.

All the metal supporting parts of the nose structure 20 are well protected, and all the brick are readily removable and replaceable. By withdrawing the brick 51, the fantail 21 can be worked upward through the clips 23 and removed,—or replaced in a reverse manner,—without disturbance of the brick 31 or of the superjacent refractory wall represented by the brick 39 resting on the beams 28 and on the brick 31. Removal of main nose brick 21 frees the corresponding filler brick 35 at either side for lateral displacement and endwise withdrawal outward.

The main arch 7 shown in Figs. 3 and 4 comprises a series of bungs extending transversely of the furnace, including bung brick 8 with heads 9 engaged by angle bar runners

10 held by clips 11 and suspended from beams 12 also extending transversely of the furnace,—or from other suitable supports. Between the bung brick 8 are pairs of "double" 5 filler brick 13, 13 supported by them through any suitable form of engagement, such as the rabbet and shoulder conformation 14. The ignition arch shown comprises brick 15 suspended by hangers 16 from supporting means 10 including the channel 17, as well as overlying brick 18 on which the adjacent filler brick 13 rest.

Inasmuch as the construction of main and ignition arches shown in Figs. 3 and 4 forms 15 no part of my present invention, it is unnecessary to describe it further here.

The nose arch 20 associated with the main arch 7 comprises sets of main brick 21 arranged in pairs, fantailwise, with their laterally undercut heads 22 back to back and held 20 between clips 23 bolted at opposite sides of sector-shaped supporting plates 24. As here shown, the supports 24 have at their rear edges depending lugs or flanges 25 for the 25 lowermost brick heads 22 to rest against. At its upper edge, each support 24 has double claw feet 26 that take over the lower flanges of a supporting member 27 that is itself supported from a couple of I beams 28 extending 30 transversely of the furnace, by means of a clamp 29 bolted fast to the upper flanges of the member 27. As shown in Figs. 3 and 4, the main arch brick 8 adjacent the nose 20 are suspended from the corresponding ends 35 of the supports 27. On the opposite ends of the supports 27 are bearing lugs 30 whereon rest "curtain" brick 31 that overlie the fantail brick 21. These brick 31 are recessed at 32 to afford pivot seats for the lugs 30, and 40 have portions 33 to engage the ends of the supports 27 and keep the brick 31 from tilting too far (counterclockwise) on the bearings 30, as their unbalance would otherwise cause them to do. As will readily be seen, the 45 weight of the brick 8 at one side of the fantail sets serves to balance the brick 31 at the other side.

Between the sets of main nose brick 21 are fantail sets of "double" filler nose brick 35 50 (Fig. 5), supported by the brick 21 by virtue of shoulder and rabbet engagement at 36. In the intervals between the main supports 27 are auxiliary supports 37 that support the curtain brick 31 corresponding to the filler 55 brick 35. In the present instance, these supports 37 are not required to help support the adjacent main arch brick 8.

Preferably, the space between the I beams 28 is open through the side walls of the furnace on which these rest, for circulation of air to cool the nose 20.

It will be seen that all the metal supporting parts of the nose structure 20 are well protected, and that all the brick are readily 65 removable and replaceable. To remove and

replace one of the curtain brick 31, it is only necessary to withdraw the corresponding brick 38 (Fig. 3) at the base of the superjacent wall 39. After this has been done and the curtain brick 31 lifted out, the corresponding brick 21 can be worked upward 70 through the clips 23 along the outer edge of the plate 24 and removed,—the grooves beneath their heads 22 permitting them to pass from clip to clip despite the relative angularity of the clips. Removal of main brick 21 frees the corresponding filler brick 35 at either side for lateral displacement and endwise withdrawal outward. 75

As shown, the various joints in the main 80 and nose arches are made tight with fireclay or other refractory cement, as usual.

In Fig. 6, the main arch 7 is composed of bungs extending lengthwise of the furnace instead of transversely. The "runners" 10 85 for the bung brick 8 have the form of channels of sufficient depth and rigidity to dispense with support at frequent intervals; they are held properly spaced by clips 40, and suspended from a couple of I beams 41 90 extending transversely of the furnace, by means of double hangers 42 taking over the lower I beam flanges. As the construction of this main arch 7 forms the subject of my pending application Serial No. 671,058, filed 95 Oct. 26, 1923, it need not be further described here.

The "nose" constructions 44 and 45 at the ends of the main arch 7 resemble that shown in Figs. 3-5, and are themselves even more 100 nearly alike. It will suffice, therefore, to describe briefly the features of the ignition arch 44 that distinguish it from the nose 20 in Figs. 3-5—marking similar parts and features with the same reference characters as in Figs. 3-5, 105 as a means of dispensing with merely repetitive description,—and then to describe briefly the specially distinctive features of the nose proper at 45.

In the ignition arch construction of Figs. 6 110 and 7, the fan-like sets of main nose brick 21 are supported directly by pairs of the sector shaped plates 46, which have engagement means 47 in the form of laterally projecting lugs or flanges along their outer edges, to take 115 the place of the pair of clips 23 on each plate 24 in Figs. 3-5. The plates 46 are secured to the channel beam supports 28 by means of clamps 29 bolted to lateral flanges 48 at the upper edges of the plates. To help support the superjacent brickwork 49, the plates 46 have nose portions 50 projecting from their outer edges, with continuations of the flanges 48 at their own upper edges. As shown, brick 51 rest on the brick 21 and 35, below the flanges 48; they can be readily removed for replacement,—or for removal and replacement of the brick 21 or 35, as described above in connection with Figs. 3-5 and the brick 31. The space behind the brick 21, 35, 51 is 120 125 130

closed or sealed off by a facing wall of brick 52, resting on the lowermost brick 21 and 35, and on laterally extending engagement means 53 in the form of lugs projecting from the 5 plates 46. These brick 52 serve to counterbalance the weight of the brickwork 49 at the other sides of the fantail sets 21, 35, and vice-versa.

In the nose proper 45, the clamp 29 is replaced by a sort of T shaped hanger 54 resting on the lower flanges of the supporting 10 I beams 28, and the projecting support 50 for the curtain brick 31 is detachably bolted to the upper outer corner of the plate 46. 15 This allows this part 50 to be replaced in case (as is apt to happen) it is exposed and burned off as a result of erosion of the brick 31 and 51,—without scrapping the entire 20 plate 46 or taking down the whole nose. The adjacent ends of the runners 10 are bolted to the plates 46 at 55, so that the weight of the brick at this end of the main arch 7 helps to counterbalance that of the brick 31, etc., and vice-versa. As shown, the plates 46 have 25 upper extensions 56 away from their outer edges, to afford bolt holes 57 for attachment of the hangers 54 in other positions, if found convenient.

Corresponding parts and features have 30 been marked with like reference characters throughout the various views, as a means of dispensing with merely repetitive description in many instances.

I claim:

- 35 1. A refractory arch nose comprising supporting means, fantail sets of main nose brick with supports at intervals along said means, and fantail sets of filler brick between and supported by said main sets.
- 40 2. A refractory arch nose comprising superstructure, fantail sets of main nose brick, a support for each of the sets at intervals along said superstructure, fantail sets of filler brick between and supported by said main sets, a second set of supports carried by said superstructure interposed between those first mentioned, and curtain brick overlying said main and filler brick sets carried by all of said supports.
- 45 3. An arch nose comprising supporting means, fan-tail sets of nose brick pivotally carried by said supporting means, and fan-tail sets of filler brick between and carried by said pivoted sets.
- 50 4. In furnace construction, the combination of supporting structural work, a series of brick supporting members arranged on said structural work, fan-tail sets of nose brick suspended from alternate supporting members, fan-tail sets of filler brick between said first sets and supported thereby, main arch bricks carried by the members which support fan-tail sets of nose brick, and curtain wall bricks supported by all of said supporting members.

5. In furnace arch construction, the combination of structural work extending transversely of the arch, a series of brick supporting members on said structural work, fantail sets of nose brick carried by said members, 70 each set being pivoted thereon as a unit, curtain brick carried by said members and means for supporting bricks of the main arch from said members.

6. In furnace arch construction, the combination of overhead structural work, a brick supporting member secured thereto, curtain brick supported by said member, fantail sets of nose brick pivotally supported by said member, and means for supporting bricks of 80 the main arch from said member.

7. A refractory arch nose comprising a supporting structure, fantail sets of main nose brick, sector-like members secured to the structure, means for independently securing 85 the brick of each set to a sector-like member, and fantail sets of filler brick between and carried by said main nose brick.

8. A refractory arch nose comprising a supporting structure, fantail sets of main 90 nose brick, sector-like members pivotally secured to the structure, means for independently securing the brick of each set to a sector-like member, and fantail sets of filler brick between and carried by said main nose brick. 95

9. A refractory arch structure comprising a supporting superstructure, brackets secured thereto at spaced intervals, fantail sets of main nose brick, sector-like members pivotally secured to alternate brackets, means 100 for independently securing the brick of each set to a sector-like member, fantail sets of filler brick between and carried by said main nose brick, curtain wall brick supported by said brackets and main arch brick supported 105 by said brackets.

In testimony whereof, I have hereunto signed my name.

BRADLEY DOBIE.
